UNITED STATES PATENT OFFICE.

WILLIAM DALTON, OF SCHENECTADY, NEW YORK, ASSIGNOR TO
AMERICAN LOCOMOTIVE COMPANY, OF NEW YORK, N. Y., A
CORPORATION OF NEW YORK.

LOCOMOTIVE-TRUCK.

No. 841,380.

Specification of Letters Patent.

Patented Jan. 15, 1907.

Application filed August 31, 1906. Serial No. 332,736.

To all whom it may concern:

Be it known that I, WILLIAM DALTON, of Schenectady, in the county of Schenectady and State of New York, have invented a certain new and useful Improvement in Locomotive-Trucks, of which improvement the following is a specification.

My present invention relates to locomotive-trucks of the general class or type of and is an improvement on that set forth in Letters Patent of the United States No. 823,491, granted and issued to American Locomotive Company as my assignee under date of June 12, 1906; and its object is to provide further and readily-adaptable facilities for controlling the lateral motion of a truck of such type, particularly at comparatively high speeds.

The improvement claimed is hereinafter fully set forth.

In trucks of the construction set forth in Letters Patent No. 823,491 aforesaid, under the conditions of weight ordinarily carried thereon and rubbing surfaces as finished on machine-tools it has been found in practice that sufficient friction is exerted to properly control the lateral movements of the locomotive when running at speeds up to, say, sixty miles per hour; but at higher speeds greater frictional resistance is required, this necessity being accentuated by the reduction of the coefficient of friction resultant upon the frictional surfaces becoming worn smooth in service.

My present invention provides means whereby the additional frictional resistance required at comparatively high speeds is exerted and the degree of friction proper to accord with the variable condition of the rubbing surfaces is rendered capable of adjustment in accordance therewith and with the speed at which the locomotive is operated.

In the accompanying drawings, Figure 1 is a plan or top view of a locomotive-truck embodying my invention; Fig. 2, a transverse section, and Fig. 3 a vertical longitudinal central section through the same.

My invention is herein exemplified as embodied in a lateral-motion locomotive-truck, which in its leading structural features and except as to those relating specifically to my present invention corresponds, substantially, with that set forth in Letters Patent No.

823,491 aforesaid. As in said Letters Patent, the frame 5 carries pedestals 5^b on its ends, in which the axle-boxes 3 are fitted, and the truck-wheels 4 are fixed upon an axle 2, the journals of which rotate in bearings 3^a in the axle-boxes upon which the truck-frame is supported through the inter-mediation of springs 9. An upper center casting 8 fits in a socket 8^a, secured to the main frame 1 of the locomotive, the lower end of the upper center casting 8 fitting in and abutting on a lower center casting 7, which in turn rests and abuts by a lower frictional face on a friction-plate 6, secured detachably to the top of the truck-frame, which, with the connected friction-plate, has the capacity of lateral motion relatively to the lower center casting 7 and the main frame of the locomotive, with which the latter is connected through the upper center casting and its socket. It will be of course understood that the truck-frame is to be provided with suitable means for returning it to normal position in line longitudinally of the locomotive after it has been diverted therefrom in passing a curve—as, for example, a centering-spring, followers, and thrust-rods, as described and shown in Patent No. 823,491 aforesaid; but as these means do not in and of themselves form part of my present invention and are, moreover, familiar to those skilled in the art they need not be herein at length set forth.

Under my present invention I impose the additional frictional resistance to lateral movement which is desired for high speeds by means of a clamping mechanism by which the movable lower center casting 7 is caused to bear with increased force against the friction-plate 6 and which also provides additional frictional surface on the upper side of the bearing portion of the casting 7. In the form herein illustrated, which has been found to be desirably adapted to the requirements of practical service, the clamping mechanism comprises two clamping-bars 16, extending longitudinally in the upper portion of the truck-frame and fitting on the upper surfaces of the flanges 7^a on the lower end of the movable center casting 7, which are clamped between the bars 16 and the friction-plate 6 by springs 17, interposed between followers 18 and 19 on vertical clamp-

ing-bolts 20, which pass through the top of the truck-frame 5, the clamping-bars 16, and the followers 18 and 19 and are provided with adjusting-nuts 21, engaging threads on their upper ends. The upper surfaces of the flanges of the lower center casting 7 thus constitute additional or secondary friction-surfaces, which abut against corresponding friction-surfaces on the lower sides of the 10 clamping-bars 16.

By means of the above-described construction or an equivalent thereof the normal load on the movable center casting may be increased to any desired extent by changing 15 the size and tension of the springs 17 and the increase be varied as required by proper manipulation of the adjusting-nuts 21. The maximum load required being determined, 20 the springs are proportioned correspondingly, and the load is applied by screwing down the adjusting-nuts to properly meet the conditions of the rubbing surfaces. It will be seen that by utilizing both the upper and lower surfaces of the flanges of the movable 25 lower center casting 7 as friction-surfaces the effect of the load is doubled in the exertion of frictional resistance.

I claim as my invention and desire to secure by Letters Patent—

30 1. The combination, in a locomotive, of a main frame, a truck-frame connected with the capacity of relative lateral movement thereto, abutting friction-faces connected to the main and truck frames respectively, and means for imparting additional frictional 35 resistance to the relative lateral movement of the main and truck frames.

2. The combination, in a locomotive, of a main frame, a truck-frame connected with 40 the capacity of relative lateral movement thereto, abutting friction-faces connected to the main and truck frames, respectively, and a clamping mechanism by which pressure is imposed upon said friction-faces.

45 3. The combination, in a locomotive, of a main frame, a truck-frame connected with the capacity of relative lateral movement thereto, abutting friction-faces connected to the main and truck frames respectively, and 50 means for imparting frictional resistance in adjustable degree to the relative lateral movement of the main and truck frames.

4. The combination, in a locomotive, of a main frame, a truck-frame connected with 55 the capacity of relative lateral movement

thereto, abutting friction-faces connected to the main and truck frames respectively, a clamping mechanism by which pressure is imposed upon said friction-faces, and a friction-face in said clamping mechanism abutting on a friction-face connected to the main frame. 60

5. The combination, in a locomotive, of a main frame, a truck-frame connected with the capacity of relative lateral movement 65 thereto, abutting friction-faces connected to the main and truck frames respectively, a secondary friction-face on a member connected to the main frame, a friction-face on a member connected to the truck-frame and abutting against said secondary friction-face, and mechanism for imposing pressure upon all of said abutting friction-faces. 70

6. The combination, in a locomotive, of a main frame, a truck-frame connected with 75 the capacity of relative lateral movement thereto, a member connected to the main frame and having upper and lower friction-faces, members connected to the truck-frame and having, respectively, friction-faces abutting against the upper and the lower friction-faces of the main-frame member, and means for imposing pressure upon 80 all of said abutting friction-surfaces.

7. The combination, in a locomotive, of a 85 main frame, a truck-frame connected with the capacity of relative lateral movement thereto, a member connected to the main frame and having upper and lower friction-faces, and mechanism for clamping said 90 friction-faces between friction-faces abutting thereon and connected to the truck-frame.

8. The combination, in a locomotive, of a main frame, a truck-frame connected with the capacity of relative lateral movement 95 thereto, a friction-plate fixed to the upper portion of the truck-frame, a member connected to the main frame and having a lower friction-face abutting on said friction-plate, clamping-bars fitting against upper friction-faces on said member connected to the main frame, bolts connecting the clamping-bars and truck-frame, springs bearing on the clamping-bars, and adjusting-nuts engaging the bolts and bearing on the springs. 100

WILLIAM DALTON.
